(57) **CLAIM**

The ornamental design for a weapon transport bag, as shown and described.

DESCRIPTION

FIG. 1 is a front top perspective view of the weapon transport bag showing my new design;

FIG. 2 is a right side elevational view thereof;

FIG. 3 is a rear elevational view thereof;

FIG. 4 is a left side elevational view thereof;

FIG. 5 is a front elevational view thereof;

FIG. 6 is a top plan view thereof;

FIG. 7 is a bottom plan view thereof; and,

FIG. 8 is a front bottom perspective view thereof.

The broken lines for the present invention as seen in FIGS. 1–8 are included for the purpose of illustrating environmental structure and form no part of the claimed design.
